CLAIM

The ornamental design for a package portion for a medical product, as shown and Described.

DESCRIPTION

This application is filed on the same day as U.S. patent application Ser. No. 13/830,009, the disclosure of which is incorporated herein by reference in its entirety.

FIG. 1 is a perspective view of an embodiment of a package portion for a medical product showing our new design; FIG. 2 is another perspective view of the package portion shown in FIG. 1, taken from a different angle;

FIG. 3 is a top view of the package portion shown in FIG. 1; FIG. 4 is a left side elevational view of the package portion shown in FIG. 1;

FIG. 5 is a front elevational view of the package portion shown in FIG. 1;

FIG. 6 is a right side elevational view of the package portion shown in FIG. 1;

FIG. 7 is a rear elevational view of the package portion shown in FIG. 1;

FIG. 8 is a bottom view of the package portion shown in FIG. 1;

FIG. 9 is a cross-sectional view of the package portion shown in FIG. 1 taken along the line 9-9 of FIG. 3;

FIG. 10 is a perspective view of another embodiment of a package portion for a medical product showing our new design;

FIG. 11 is another perspective view of the package portion shown in FIG. 10, taken from a different angle;

FIG. 12 is a top view of the package portion shown in FIG. 10; FIG. 13 is a left side elevational view of the package portion shown in FIG. 10;

FIG. 14 is a front elevational view of the package portion shown in FIG. 10;

FIG. 15 is a right side elevational view of the package portion shown in FIG. 10;

FIG. 16 is a rear elevational view of the package portion shown in FIG. 10;

FIG. 17 is a bottom view of the package portion shown in FIG. 10; and,

FIG. 18 is a cross-sectional view of the package shown in FIG. 10 taken along the line 18-18 of FIG. 12.

The embodiment of FIGS. 10-18 is substantially the same as the embodiment of FIGS. 1-9, with the exception of certain elements, shown, for example, in FIGS. 12, 17, and 18.

The broken lines showing symbols and alphanumeric characters are for the purpose of illustrating portions of the article, and form no part of the claimed design.
